CLAIM

The ornamental design for a child's backpack, substantially as shown and described.

DESCRIPTION

FIG. 1 is a front perspective view of a child's backpack having a hinged transparent front display frame in a closed position; FIG. 2 is a rear perspective view of the child's backpack of FIG. 1; FIG. 3 is a front elevation view of the child's backpack of FIG. 1; FIG. 4 is a rear elevation view of the child's backpack of FIG. 1; FIG. 5 is a left elevation view of the child's backpack of FIG. 1. FIG. 6 is right elevation view of the child's backpack of FIG. 1; FIG. 7 is a top plan view of the child's backpack of FIG. 1; FIG. 8 is a bottom plan view of the child's backpack of FIG. 1; FIG. 9 is a front perspective view of the child's backpack of FIG. 1 with its hinged transparent front display frame in an open position; FIG. 10 is a rear perspective view of the child's backpack of FIG. 9; FIG. 11 is a front elevation view of the child's backpack of FIG. 9; FIG. 12 is a rear elevation view of the child's backpack of FIG. 9; FIG. 13 is a left elevation view of the child's backpack of FIG. 9. FIG. 14 is right elevation view of the child's backpack of FIG. 9; FIG. 15 is a top plan view of the child's backpack of FIG. 9; and, FIG. 16 is a bottom plan view of the child's backpack of FIG. 9. The dashed lines of the round protrusions on the backpack's back surface in FIGS. 2, 4 to 8, 10, and 12 to 16 indicate the protrusions form no part of the claimed design.
